2 Sheets-Sheet 2

UNITED STATES PATENT OFFICE.

WILLIAM BAYLEY, OF SPRINGFIELD, OHIO.

SILO.

Application filed January 26, 1926. Serial No. 83,887.

My invention relates to silos and the like, and more particularly to a silo or tank structure formed from sheet metal or similar wall sheets.

Whereas it is the usual practice to construct sheet metal silos, tanks and the like by interconnecting the wall sheets into horizontal courses, the present invention contemplates courses with their length or major dimensions vertically disposed, and the horizontal joints or connections between each successive vertically arranged sheets preferably offset or staggered. To this end, the structure, which is of substantially cylindrical form is provided upon its interior with spaced studding or struts preferably comprising angle bars, which extend vertically from the foundation to the top of the structure, and to which the vertical margins of the wall sheet are attached by bolts or rivets, such sheets being provided with marginal shoulders, by which they are interconnected to resist internal pressure or bursting strain independent of the attachment bolts, thereby relieving the attachment bolts of shear strain. The structure is provided with a panel having therein a succession of access openings, which door panel is designed to resist the internal pressure or bursting strain equally with the peripherally arranged wall sheets, so that such strains are proportionately distributed among the various wall sheets, throughout the full height of the structure.

The object of the invention is to simplify the structure, as well as the means and mode of interconnecting the wall sheet and structural parts, whereby such silos will not only be cheapened in construction, but will be more efficient in use, capable of being easily and quickly assembled, of maximum strength and durability, and unlikely to get out of repair.

A further object of the invention is to provide a sheet metal silo construction, which will afford minimum obstruction or interference to the free descent of the ensilage.

A further object of the invention is to provide improved means for reinforcing such silo or tank structures, against internal pressure, or bursting and shearing strains.

A further object of the invention is to provide an improved door panel construction, which will afford a vertical succession of closely positioned access openings, while maintaining maximum strength and resistance, equal to that of the remainder of the structure.

A further object of the invention is to provide improved means for joining contiguous wall sheets.

With the above primary and other incidental objects in view as will more fully appear in the specification, the invention consists of the features of construction, the parts and combinations thereof, and the mode of assembly or their equivalents as hereinafter described and set forth in the claims.

In the accompanying drawings, wherein is shown the preferred, but obviously not necessarily the only form of embodiment of the invention, Fig. 1 is a top plan view of the assembled silo or tank structure, with the roof or cover removed. Fig. 2 is a side elevation thereof, showing the left hand half of the structure in section, and looking toward the interior of the door or access opening panel, while the right half of the structure is shown in exterior elevation. Fig. 3 is an enlarged detail view of a portion of the door or access opening panel showing the disposition of the access opening and the mode of reinforcement. Fig. 4 is a detail sectional view of the construction shown in Fig. 3. Figs. 5 to 9 inclusive are developed detail views illustrating the interconnection of the wall sheets with each other and with the studding and frame of the access opening panel, the parts being shown disconnected in the several views 5 to 8, and as finally assembled in Fig. 9. Figs. 10 to 17 inclusive illustrate various methods of interconnecting the wall sheets one with another. These forms of joints apply particularly to the vertical margins of the wall sheets, although they may be applied also to horizontal joints. Figs. 18 to 20 illustrate different methods of connecting the wall sheets or horizontal joints.

Like parts are indicated by similar characters of reference throughout the several views.

Referring to the drawings, 1—1 is a plurality of vertical studs or angle bars, which at their lower ends are embedded in a foundation 2 of concrete or masonry. These vertical angle bars or studdings although located interiorly of the walls of the structure, are of uniform continuous dimension and thus afford no obstruction for the lodgment of ensilage. By being firmly anchored in the foundation 2, such angle studdings resist all wind pressure, and materially assist and reinforce the side wall sheets in resisting internal bursting strain. Secured to the vertical studs or angle bars 1—1 are wall sheets 3, preferably of

sheet metal, but which may be of other suitable material. These wall sheets 3 are vertically disposed upon the angle bars or studs 1, that is to say, the sheets are arranged with 5 their length or major dimension upright. The sheets of each vertical series are preferably offset or staggered relative to each other to break the horizontal joints, so that in no instance will the horizontal joint between the 10 sheets be continuous circumferentially of the structure. These wall sheets 3 are so joined and arranged that approximately the full area of the sheet is utilized. The sheets are joined by abutting the inturned marginal 15 edges of one sheet upon that of another, whereby the bursting strain is transmitted directly from one sheet to another, independent of the attachment bolts or rivets which are thus relieved of shearing strain. The 20 preferred form of joint is illustrated in Figs. 5 to 9. The vertical marginal edges of the sheet are bent reversely upon the sheet to parallelism, as shown at 4. These successive joined sheets are reversed so that the reverse 25 marginal edges of the sheets are on the outer faces of alternate sheets, and on the inner faces of the intermediate sheets. The Figs. 5 to 8 illustrate this succession of joints, in 30 which Fig. 5 illustrates the interlocking connections of the wall sheet 3 to the door or access opening panel, while Fig. 7 shows the relation of the outwardly faced reverse marginal edge 4 of the first sheet 3 of the series and the inwardly faced reverse marginal 35 flange of the second sheet 3^a of the series which is to be interconnected with the first sheet 3. Fig. 8 shows the relation of the interlocking marginal edges of the second sheet 3^a and a third sheet 3^b, which occurs coincident with 40 the second of the angle bar studs or studding 1. These wall sheets are provided with punched holes in proximity to their reversed margins, to receive clamp bolts 5. In the final assembly or interconnection of the sheets, the 45 reverse margins of successive sheets are arranged in overlapping relation, as shown in Fig. 9 with the inturned edges 4—4 of the successive sheets abutting one upon the other. They are clamped in this position by the bolts 50 5 which are preferably provided with a collar or washer 6, which serves to hold the overlapped sheets in interlocked relation with their marginal inturned edges abutting one upon the other to resist internal pressure or 55 bursting strain, wholly independent of the clamp bolts 5. The bolt 5 is thus relieved of all shearing strain and serves merely the purpose of holding the sheet against the studding or angle bar 1; without however, assuming any resistance to shearing or pulling strains of the sheet. This same idea of transmitting tension strains from one sheet to another independent of the attachment bolts, by subjecting the edges of the inturned 60 margins to the bursting or shearing strains, 65

may be effected in other ways, as has been shown in Figs. 10 to 16. For example in Fig. 10 a sealing strip 7 is employed having in-turned marginal edges which interlock between the inturned marginal edges 4' of the wall sheets to serve as a coupling member between the sheets. In this case, the attachment bolt 5 extends through registering notches in the folded abutting margins of the wall sheets 3—3 and thence through the sealing or coupling strip 7. As in the construction before described, the bolt 5 serves merely as a clamp or attachment bolt, while the pulling or shearing strain is resisted solely by the interlocked coupling strip 7. In Fig. 11 this construction has been modified by employing a channel-shaped coupling strip 9, upon the internal shoulders 10 of which, the edges of the inturned margins 4 of the wall sheet abut. In this case, the wall sheets are separated at their forward edges sufficiently to permit the extension of the clamp bolt 5 therebetween, without intersecting the wall sheets. This clamp bolt 5 engages with the coupling strip 9, and serves to clamp the reversed margins of the wall sheet between the strip 9 and the angle bar or studding 1.

The construction shown in Fig. 12 is quite similar to that shown in Fig. 11, except that the folded margins of the wall sheets are brought closely together necessitating registering notches in such folded margins for the accommodation of the clamp bolt 5. Otherwise the sheets are connected and the shearing or pulling strain resisted by the channel-shaped coupling strips 9, having its internal shoulders 10, upon which abut the edges of the reverse margins 4 of the wall sheets.

Fig. 13 illustrates a further modification wherein the wall sheets 3 are formed with marginal offsets or rabbits 11, which engage within a channel shaped coupling strip 12. The clamp bolts 5 extend through the overlapped portions of these offset margins of the sheet, and thence through the channel shaped coupling strip 12 to clamp the sheets in their overlapped relation. In this form of joint an auxiliary filler strip 13 is disposed interiorly of the overlapped offset or rabbitted portion of the sheet, around which such offset portions extend. Obviously, such filler strip may if desired be formed integrally with the angle bar 1. In Fig. 14, the inturned marginal edges of the wall sheet are shown in the same abutting relation as in Fig. 9, but in addition thereto a channel shape coupling strip 14 exteriorly of the overlapped courses of the sheet serves to clamp the sheets in interlocked relation under influence of the clamp bolts 5, and so reinforce such joints. Fig. 15 is quite similar to the construction shown in Fig. 10, except that the margins of the coupling strip are not interposed between the reverse marginal edges of the wall sheet. In this construction, the

folded edges of the sheet are arranged in close contact or abutting relation as in Fig. 12, and in lieu of the internally shoulder or channel shaped coupling strip shown in Fig. 5 12, there is employed a strip of sheet metal having its margins inturned in somewhat the same manner as the wall sheet, which register with and abut upon the edges of such wall sheet.

10 Fig. 16 is quite similar to Fig. 12 and Fig. 17 quite similar to Fig. 15, except that in these figures a double series of attachment or clamp bolts are employed.

Thus in whatever form the joint between 15 successive sheets may embody, the strain incident to internal pressure is transmitted directly from one sheet to the other, through the reverse marginal edges wholly independent of the attachment or clamp bolts, thus 20 relieving the latter from shearing strain. The same form of joint or interconnection may be utilized for horizontal joints as well as for the vertical joints. However, for 25 economy of manufacture and ease of assembly, the heretofore described method of connection as illustrated in Figs. 5 to 16 are preferably applied to the vertical seams or joints. At their upper and lower ends, the 30 wall sheets 3 are preferably outturned or flanged as at 15, in Fig. 18. The upper flange 35 of such joint, which is the lower flanged end of the wall sheet is further downturned as at 16 to overhang the lowermost flange 15 of the joint and exclude moisture from between such flanges and project the nut and thread 40 of the clamp bolt 17, by which such outturned abutting flanges are interconnected. In lieu 45 of this flanged joint at the upper and lower ends of the wall sheet, such wall sheets may be abutted edge to edge as shown in Fig. 19 and then interconnected by an overlapping 50 channelled band or hoop 18, which is connected at spaced intervals to the wall sheets 3 by short clamp bolts 19. As shown in Fig. 19, 55 these clamp bolts are of special formation, having rather low rounded heads, which will afford minimum resistance to the descent of ensilage in close proximity to the wall. In Fig. 20 substantially the same construction 60 previously illustrated in Fig. 12 is shown applied to the horizontal joints between the end of the sheet. In such construction the upper and lower marginal ends of the sheets are reversed upon themselves to parallelism, 65 and overlapped by a channelled band or hoop, the internal shoulders of which abut upon the reverse margins of the sheet.

Intermediate two of the vertical spaced angle iron or studding 1-1, there is provided 60 a door panel, located at 20, Figs. 1 and 2, and illustrated in detail in Figs. 3 and 4. This door or access opening panel comprises 65 two spaced upright angle bars or struts 21-21, which are located in aligned registry with the internal studding 1-1 at opposite

sides of the access openings. These exterior struts 21 are transversely interconnected at spaced intervals by tie bars 22, preferably though not necessarily of channel form. These channel bars are preferably united to 70 the struts 21, by welding, but may be riveted or bolted as conditions require. The structural frame thus formed by interconnected struts and cross bars is reinforced by triangular plates 23. These reinforcement 75 panels are preferably formed by bending backward along diagonal lines, upon itself, the corners of a sheet of metal, such as is used to form the side walls 3. This folded section 23 of sheet metal is inturned at its marginal end as 80 at 24, (Fig. 4), for interlocking engagement with the inturned margin 4 of the wall sheet 3. Inasmuch as this forms a three-fold thickness of metal at this joint, the reverse triangular flaps or folds of the reinforcement sheet 23 85 are also marginally reversed as at 25 (Fig. 4). This reversal of the marginal edge at 25 serves as a filler or spacer, intermediate the frame strut 21 and the internal angle bar stud 1. The reinforced panel including the vertical 90 struts 21 and cross bars 22, with their triangular braces or reinforcement plates 23 is bolted or riveted to the internal angle bar studs 1-1 at opposite sides of the access opening, and serves to complete the annular connection 95 of the wall sheets. The construction of this access opening panel is such that its strength is equal to or greater than that of the distributed wall sheets 3, so that notwithstanding the fact that such panel contains a series of 100 closely positioned access openings, it possesses also the necessary requisite strength to resist the internal pressure or bursting strain to which the silo may be subjected. The access 105 openings 26, formed intermediate the cross bars 22 of the panel plates are defined by the triangular brace plates or reinforcement plates 23, as diagonal openings or access openings of rectangular form turned with their 110 diagonal corners in a vertical aligned position. This enables the top and bottom of such access openings to be brought closely together, separated only by the width of the transverse panel tie bar 22, so that in removing ensilage 115 it is necessary to lift it only a very small distance at any time, in order to pass it through one or another of the openings 26. At the inner side of each of the access openings 26, there is provided a closure door 27, the margins of which are flanged or offset at 120 28 to overlap the inner angle bar or studdings 1-1, and to enable such closure doors to bear tightly against the triangular brace plates 23. These closure doors are hinged at their upper 125 extremities as at 29 to the interior of the transverse tie bars 22. They are held in their closed positions by pivoted buttons or fingers 30, carried by the lower portion of the door, and turned into overlapping relation with the reinforcement or brace plates 23. Such lock- 130

ing buttons or fingers may be provided at the bottom of the closure door for engagement with the transverse tie bar 22, as shown at 31 in Fig. 3. By the provision of a door panel 5 having therein a series of closely associated access openings, as described, the erection of such a panel is very materially simplified. Such door panel may be assembled completely or in extended sections at the factory. The 10 door panel being factory constructed ready to set upright, the opposite sides of the panel may be connected with the structure, by the interlocking of the wall sheet joints, by unskilled labor. When so constructed the resistance to 15 bursting strain is uniformly distributed, and the structure is not at all weakened by the provision of the closely associated access openings, inasmuch as the reinforced panel or frame containing such access opening possesses 20 strength and resistance to bursting strain, equal to or greater than a like area of wall sheets. While any transverse obstruction within the silo structure, which would afford lodgment for the ensilage is objectionable, the provision of internal vertically disposed angle bar studs 1-1 is not susceptible 25 to this objection inasmuch as these bars are continuous throughout their vertical extent and while reinforcing the walls of the structure, they afford no interference with the movement of the ensilage, which will descend along such studdings 1-1 as freely as along the interior faces of the wall sheet intermediate such studding. The construction 30 has the further advantage of enabling the use of full size metal sheets in upright or vertical arrangement, enabling the horizontal joints to be broken or offset, which is of material advantage in distributing strain and avoiding the shearing effect encountered very often 35 when the wall sheets are arranged in horizontal courses or tiers. The internal reinforcement afforded by the vertical spaced angle bar struts serves to securely anchor the structure to the foundation and materially increases its 40 resistance to wind pressure, as well as stiffening the walls and increasing their resistance to internal bursting pressures.

Cross reference is made to co-pending application, Serial No. 83886 filed of even date herewith.

From the above description it will be apparent that there is thus provided a device of the character described possessing the 55 particular features of advantage before enumerated as desirable, but which obviously is susceptible of modification in its form, proportions, detail construction and arrangement of parts without departing from the 60 principle involved or sacrificing any of its advantages.

While in order to comply with the statute the invention has been described in language more or less specific as to structural features, 65 it is to be understood that the invention is

not limited to the specific details shown, but that the means and construction herein disclosed comprises the preferred form of several modes of putting the invention into effect and the invention is, therefore, claimed in 70 any of its forms or modifications within the legitimate and valid scope of the appended claims.

Having thus described my invention, I 75 claim:

1. In a silo construction, a substantially cylindrical tank like structure, comprising a series of spaced upright studs and a plurality of wall sheets secured thereto, said wall sheets being arranged with their major dimension vertically disposed and joined on vertical lines coincident with said studs, abutment shoulders formed in spaced relation with the edges of the sheet, coupling strips overlapping the joints and having interlocking engagement with the abutment shoulders of adjacent sheets and connecting the sheets into a continuous strain resistant series and attachment members connecting the coupling strips with the studs, the internal bursting strains of the structure being transmitted from one sheet to another through said interlocking joints independent of the attachment means to said studs, adjacent sheets being vertically offset to afford non-alined horizontal joints, a door panel and interlocking connections between the door panel and the wall sheets at opposite sides thereof completing the cylindrical structure.

2. In a silo construction, a substantially cylindrical tank like structure, formed from sheet metal, a door panel forming a part of said structure, a series of spaced vertically arranged studs arranged interiorly of the sheet metal walls of the structure, the margins of the sheets being reversely bent to parallelism, abutment shoulders formed by said reversely bent margins, said abutment shoulders being interconnected with each other to form a continuous strain resistant series of sheets, and means connecting said sheets with said studs, said means being relieved of shearing strains by the interconnection of said sheets.

3. In a silo, a substantially cylindrical tank like structure, the walls of which include a plurality of metallic wall sheets arranged in vertically disposed alinement, the sheets of successive vertical courses being offset vertically to interrupt the continuity of horizontal joints, the margins of succeeding sheets being reversely bent to parallelism to form reversely facing abutment shoulders having interlocked engagement with each other to resist internal bursting strains independent 115 of other supporting means, a door panel and interlocking abutment shoulders upon the door panel and adjacent wall sheets thereby completing the cylindrical structure.

4. In a silo construction, a foundation, an 130

annular series of vertically disposed spaced studs anchored in said foundation, a plurality of metallic wall sheets interconnecting the vertical anchored studs one with another, interlocking joint connections between succeeding sheets by which the sheets are enabled to resist internal bursting strains independent of their connection with the studs, a door panel and interlocking joint connections between the door panel and adjacent wall sheets to thereby form in conjunction with said wall sheets a substantially cylindrical tank like structure.

5. In a silo construction of the character described, a tank like structure, the walls of which include a plurality of metallic wall sheets arranged in a succession of vertical courses, the marginal edges of the sheets being reversed, and coupling means upon which 15 the marginal edge of each sheet abuts, connecting the sheets into a tension resistant series through which strains are distributed uniformly and enabling the interconnected wall sheets to resist tension strains incident 20 to internal pressure independent of other supporting means.

6. In a silo construction of the character described, a tank like structure, the walls of which include a plurality of metallic wall 30 sheets arranged in a succession of vertical courses, said sheets being formed with marginal shoulders, and a complementary member having corresponding shoulders upon which the shoulders of a plurality of sheets 35 abut, connecting the sheets into a tension resistant band through which the bursting strains are distributed and affording substantially uniform resistance to tension strains incident to internal pressure.

40 7. In a construction of the character described, a structure having walls formed from a succession of metallic sheets, the margins of the sheets being reversed upon themselves to parallelism to form stop shoulders, said 45 stop shoulders of successive sheets being coupled one to another into a continuous tension resistant band through which strains are distributed from one sheet to another enabling resistance to tension strains incident to internal pressure within the structure.

50 8. In a construction of the character described, a structure having walls formed from a succession of metallic sheets, the margins of the sheets being reversed upon themselves to parallelism to form stop shoulders, said 55 stop shoulders of successive sheets being abutted one upon another to afford a continuous tension resistant band to enable 60 resistance to tension strains.

9. In a construction of the character described, a structure having walls formed from a succession of metallic sheets, the margins of the sheets being reversed upon 65 themselves to parallelism to form stop shoul-

ders, and a reversely shouldered member, the shoulders of which abut upon the oppositely disposed shoulders of different sheets into a continuous tension resistant band through which the pulling strain is transmitted from one sheet to another in opposition to internal against tension strains.

10. In a silo construction of the character described, a series of spaced upright studs, a plurality of metallic sheets attached to said 70 struts to form a tank like structure, and vertically disposed joints between successive sheets formed by reversely abutting said sheets one upon another, forming a continuous 75 tension band throughout which pulling strain is distributed from one to another in opposition to tension strains incident to internal pressure within the structure, independent of the attachment of said sheets to the struts.

85 11. In a silo construction of the character described, a plurality of spaced upright studs, a plurality of wall sheets attached thereto, said wall sheets being interlocked one to another upon vertical joints into a continuous 90 strain resistant succession throughout which tension strains are transmitted from one sheet to another independent of their attachment to said studs.

12. In a silo construction of the character 95 described, a plurality of spaced upright studs, a plurality of wall sheets attached thereto, said wall sheets being reversely bent along their vertical margins to form vertical stop shoulders, the vertical shoulders of one sheet 100 being abutted upon another sheet to form an interlocked succession throughout which tension strains are transmitted from one sheet to another to enable the sheets to resist internal bursting strains independent of their attachment to said studs.

105 13. In a silo construction of the character described, a plurality of spaced upright studs, a plurality of wall sheets attached thereto, the marginal sheets being reversely 110 bent along their marginal edges to form vertical stop shoulders, and coupling means interconnecting the reversed margins of different sheets to form a continuous tension 115 resistant band throughout which tension strains are distributed from one sheet to another to enable their resistance of internal bursting strains independent of their attachment to said struts.

120 14. In a silo construction, a tank like structure including a door panel comprising spaced upright studs, transverse tie bars interconnecting the struts, and substantially triangular reinforcement plates attached to the studs and tie bars at the angles thereof, 125 and defining intermediate said tie bars, substantially rectangular openings the diagonal corners of which are disposed in vertical alignment.

125 15. In a silo construction, a tank like struc-

ture having walls of sheet material, and a door panel comprising upright spaced studs, transverse bars connecting said studs to afford therebetween a vertical succession of access openings, and means for interlocking the panel with the walls of the structure to enable resistance to tension strains.

16. In a silo construction, a tank like structure, having walls of sheet material, and a door panel comprising upright spaced studs, transverse bars connecting said studs to afford therebetween a vertical succession of access openings, vertical abutment shoulders formed upon the walls of the structure, adjacent to the door panel and corresponding abutment shoulders formed upon the door panel having interlocking engagement with those of the structure wall to resist tension strains.

17. In a silo construction of the character described, wherein a tank like structure has walls of sheet material the vertical margins of which are reversed to form stop shoulders for engagement of a door panel and a door panel therefor, including upright spaced studs transverse tie bars connecting the studs, brace plates diagonally disposed upon said studs and tie bars defining access openings intermediate the tie bars, vertical stop shoulders formed adjacent to the margins of the reinforcement plates of said panel and engageable with those of the structure wall to enable resistance of tension strains.

18. As an article of manufacture, a door panel for silos and the like, comprising parallel spaced studs, transverse tie bars interconnecting the struts, diagonally disposed brace members overlapping the angles of the studs, and tie bars, said diagonal brace members defining a succession of substantially rectangular access openings having their diagonally opposite corners in vertical alignment.

19. As an article of manufacture, a door panel for silos and the like, comprising parallel spaced studs, transverse tie bars intercon-

necting the studs, and brace members diagonally connecting the struts and tie bars and forming therebetween a succession of polygonal access openings.

20. As an article of manufacture, a door panel for silos and the like, comprising parallel spaced studs, transverse tie bars interconnecting the studs, diagonal brace members arranged transversely of the angles of the struts and tie bars, and closure doors arranged in overlapping relation with the tie bars and brace members.

21. As an article of manufacture, a door panel for silos and the like comprising parallel spaced studs, transverse tie bars interconnecting the studs, diagonal brace members arranged transversely of the angles of the studs and tie bars, and closure doors hinged to said tie bars, at the tops of the access openings, the margins of which overlap said openings, and pivoted locking buttons carried by the doors and overlapping the diagonal brace members.

22. As an article of manufacture, a door panel for silos and the like, including a pair of spaced upright angle bars, transverse channel bars interconnecting the upright angle bars in spaced relation, reinforcement plates extending diagonally across the angles of the upright angle bars and transverse channel bars, and vertically disposed shoulders formed on the inner face of said panel for engagement with corresponding shoulders upon the wall of a silo structure to enable resistance to tension strains.

23. As an article of manufacture, a door panel for silos and the like, comprising parallel spaced vertical studs, transverse tie members interconnecting the studs and angularly disposed wall sections extending intermediate the studs and separating the intermediate space into a plurality of spaced access openings.

In testimony whereof, I have hereunto set my hand this 5th day of January, A. D. 1926.

WILLIAM BAYLEY.
